(57) **CLAIM**

The ornamental design for a combination interlock and stopper device for a food waste disposer, as shown and described.

DESCRIPTION

(21) Appl. No.: **29/251,519**

FIG. 1 is a top perspective view of the combination interlock and stopper device for food waste disposer showing our new design;

(22) Filed: **Jan. 9, 2006**

FIG. 2 is a bottom perspective view.

(51) **LOC (8) Cl.** 31-00

FIG. 3 is a top view.

(52) **U.S. Cl.** **D7/375**

FIG. 4 is a bottom view.

(58) **Field of Classification Search** D7/375,

FIG. 5 is a front view (the rear view is identical); and,

D7/372; 4/DIG. 4, 629, 292, 652; D15/21;
241/46.016, 81, 46.013, 46.014, 46.015,
241/46.018

FIG. 6 is a side view (the opposite side is identical).

See application file for complete search history.
